ALFRED L. ATHERTON, OF EDGEWOOD PARK, PENNSYLVANIA, ASSIGNOR TO WESTINGHOUSE ELECTRIC AND MANUFACTURING COMPANY, A CORPORATION OF PENNSYLVANIA

STARTING DEVICE FOR VAPOR-CONVERTERS.

1,371,966.

Specification of Letters Patent. Patented Mar. 15, 1921.

Continuation of application Serial No. 63,997, filed November 29, 1915. This application filed March 19, 1918. Serial No. 223,334.

To all whom it may concern:

Be it known that I, ALFRED L. ATHERTON, a citizen of the United States, and a resident of Edgewood Park, in the county of Allegheny and State of Pennsylvania, have invented a new and useful Improvement in Starting Devices for Vapor-Converters, of which the following is a specification, this being a continuation of copending application, Serial No. 63,997, filed November 29, 1915.

My invention relates to starting apparatus for vapor converters, and it has for its object to provide a device of the character indicated that shall be simple and inexpensive to manufacture and effective in operation.

In the accompanying drawing, Figure 1 is a diagrammatic view of a vapor converter, together with its attendant supply, load and starting circuits and starting apparatus, embodying a preferred form of my invention; and Fig. 2 is a diagrammatic view of a modification of the structure shown in Fig. 1.

In the ordinary vapor converter, it is necessary that the electrode reluctance at the cathode be broken down before rectification can begin. One method of accomplishing this purpose comprises an auxiliary anode which is brought into contact with the cathode by means of a tilting magnet which tilts the converter. When the auxiliary anode and the cathode are in engagement, the winding of the tilting magnet is short-circuited and allows the converter to return to its original position, breaking the contact between the electrodes, whereupon, a small spark is struck and suitable conditions are established for the initiation of a power arc from the main anodes. An objection to this method is that the tilting magnet must be energized from a winding which may be short-circuited without any damage resulting therefrom. This necessitates the use of a special additional transformer which adds materially to the cost of the outfit.

By my invention, I provide a converter in which the auxiliary anode and the cathode are in contact with each other and in series with the winding of the tilting magnet when the converter is in its inactive

position. When a current passes through the anode-cathode mercury connection the 55 tilting magnet is energized to break the mercury connection, thus producing the necessary starting spark. The source providing current for the tilting magnet is never short-circuited and may, therefore, be 60 a part of the main transformer. I provide also means whereby the converter may be oscillated continuously, alternately making and breaking an alternating-current circuit between the cathode and an anode until 65 such time as a break occurs during an alternating-current wave of such polarity as to destroy the negative-electrode reluctance of the cathode. The oscillating device thereupon operates as a locking device to hold 70 the converter in such position that the auxiliary anode is out of contact with the cathode.

Referring to Fig. 1 of the accompanying drawing for a more detailed understanding of my invention, I show a converter of the 75 ordinary type at 1, said converter comprising an evacuated glass container provided with main anodes 2 and 3, a main liquid cathode 4 and an auxiliary starting anode 5. The container 1 is pivotally mounted 80 and the upper portion thereof tends to be drawn to the left by a suitable spring 7. The upper portion of the container 1 may be drawn to the right, in opposition to the spring 7, by a suitable spring 8 connected 85 to the armature 9 of a tilting magnet 10 provided with energizing windings 11 and 12. The main anodes 2 and 3 are connected, respectively, to the terminals of a transformer winding 13, as is customary in the 90 art, and the cathode 4 is connected to the mid-point of the winding 13 through the winding 12 and a load 14 which may be any direct-current apparatus, such, for example, as a storage battery. The winding 11 is 95 connected between the right-hand terminal of the winding 13 and the starting anode 5 through a suitable current-limiting device 15.

Having thus described the arrangement of 100 the system, the operation is as follows. At the outset, the container 1 is in the full-line position, under the influence of the spring 7, and the mercury in the anode 5 is in contact with that in the cathode 4. Upon 105 energization of the winding 13, alternating

current flows from the right-hand terminal of the source through the rheostat 15, the actuating coil 11, the electrodes 5 and 4, the holding coil 12 and the battery 14 and 5 returns to the mid-point of the source. Assuming a current wave to flow through the path in such direction as to pass from the cathode 4 to the anode 5, a powerful spark will ensue because said wave is assisted by 10 the voltage of the battery 14 but the break between the cathode and the starting anode brought about by the energization of the magnet 10 will produce no rectification, because, with the assumed operation of current flow, the negative-electrode reluctance 15 of the auxiliary anode 5 only is broken down, and the container returns to its aforementioned position. When, however, a current wave flows in the starting circuit from 20 the anode 5 to the cathode 4; that is to say, in opposition to the electromotive force of the battery 14, there will be a pronounced spark at the surface of the cathode because of the necessary preponderance of the voltage 25 of the supply in any battery-charging system, and said spark breaks down the negative-electrode reluctance of the cathode 4. The rectification of load current from the anodes 2 and 3 at once ensues, and the 30 passage of the load current through the winding 12 maintains the armature 9 in its closed position, holding the container 1 in the dotted-line position, with a break between the anode 5 and the cathode 4, and 35 resultant non-energization of the winding 11. The rectifier is maintained in active condition by inherent leakage reactance in the supply transformer or, if desired, by the insertion of inductive apparatus in the 40 load circuit.

It will be observed that, by my structure, I combine the functions of the distinct tilting and locking magnets hitherto employed and, at the same time, provide a very effective method of starting.

I find, with ordinary ratios of oscillating mass to spring constants, that the container does not swing over to the operative position at once but tends to oscillate between 50 the springs 7 and 8, with the armature 9 in the closed position.

I find also, with the arrangement shown in Fig. 1, that half-wave impulses flowing from the cathode 4 to the anode 5, during 55 the starting operation, may cause objectionable noises and vibration.

In order to avoid such difficulties, recourse may be had to the system shown in Fig. 2, wherein the arrangement of elements 60 is the same as in Fig. 1, except that the spring 7 is replaced by a gravity control, provided by permitting the vertical axis of the container 1 to swing approximately 20° from the vertical in the inoperative position, and, furthermore, the starting current

is derived from an auxiliary transformer winding 16 rather than from the main transformer winding.

The gravity control permits little or no oscillation of the container 1, after the 70 armature 9 has closed, and procuring the starting current from the small auxiliary winding minimizes the noise and vibration due to half-waves of the wrong direction. Also, in this modification, the energizing 75 winding 11 of the tilting magnet 10 is continuously energized to maintain the container 1 in its operative position, thereby dispensing with the winding 12.

A relay 17, which is provided with an energizing winding 18 connected in series with the cathode 4, when deenergized, provides a path from the winding 16, through the magnet winding 11, contacts 19 of the relay 17 and, through cathode 4 and the anode 5, 85 back to the winding 16. The current passing through the winding 11 tilts the container to break the mercury connection between the cathode 4 and anode 5, as previously described. If the negative-electrode 90 reluctance of the cathode 4 is broken down, current will immediately flow from the anodes 2 and 3 to the cathode 4 and through the winding 18 of the relay 17, causing the relay 17 to operate to connect the winding 95 16 across the winding 11 through contacts 20, thus preventing any interruptions of the tilting-coil circuit after the converter has started to operate.

If current is flowing from the cathode 4 100 to the anode 5 at the instant at which the mercury connection is broken, the negative-electrode reluctance of the anode 5 only is broken down, causing current to tend to flow from the anodes 2 and 3 to the anode 5. 105 This is, of course, objectionable. In order to prevent this, the auxiliary secondary winding 16 is made of such value that the sum of the voltages of the auxiliary winding 16, the battery 14, the voltage drops throughout the circuit and the voltage of that half of the winding 13 which is connected to the positively charged electrode is equal to the voltage of the other half of the winding 13, which, being negatively charged, is not carrying any current. This will result in current flowing to the auxiliary anode 5 during that half of the wave in which the current of the auxiliary winding 16 aids that of the main winding but will result in no 110 current flowing in the following half wave, during which the current of the auxiliary winding opposes that of the main winding. This will, of course, cause a break in the rectified current stream and cause the converter to return to its original position and begin the tilting operation over again.

While I have shown my invention in its preferred form, it will be obvious to those skilled in the art that it is susceptible of va- 115

rious minor changes and modifications without departing from the spirit thereof, and I desire, therefore, that only such limitations shall be placed thereupon as are imposed by the prior art or are specifically set forth in the appended claims.

I claim as my invention:

1. The combination with a transformer comprising a main and an auxiliary secondary winding, of a vapor converter comprising two main anodes connected to the terminals of said main winding, a cathode connected to substantially the mid-point of said main winding through a battery, and an auxiliary anode connected to said cathode through said auxiliary winding, the algebraic sum of the electromotive forces of the auxiliary winding, the battery, the potential drops throughout the circuit and one-half of the main winding being substantially equal to the electromotive force of the other half of the main winding.

2. The combination with a transformer provided with a secondary winding and an auxiliary source of electromotive force, of a vapor converter comprising a pivotally mounted container provided with two main anodes, an auxiliary anode and a cathode, and a magnet adapted to tilt said container, said main anodes being connected to the terminals of said secondary winding, said cathode being connected to substantially the mid-point of said winding, and said auxiliary anode being connected in series with the said cathode, the said auxiliary source of electromotive force, and the energizing winding of said tilting magnet during starting operation.

3. The combination with a transformer comprising a main and an auxiliary secondary winding, of a vapor converter comprising a pivotally mounted container provided with two main anodes, an auxiliary anode and a cathode, and a magnet adapted to tilt said container, said main anodes being connected to the terminals of said main winding, said cathode being connected to substantially the mid-point of said main winding, and said auxiliary anode being connected in series with said cathode through said auxiliary winding and through the energizing winding of said magnet during the starting operation.

4. The combination with a transformer comprising a main and an auxiliary secondary winding, of a vapor converter comprising a pivotally mounted container provided with two main anodes, an auxiliary anode and a cathode, and a magnet adapted to tilt said container, said main anodes being connected to the terminals of said main winding, said cathode being connected to substantially the mid-point of said main

winding, and said auxiliary winding being connected to the energizing winding of said tilting coil at all times and through the said auxiliary anode and cathode during starting operation.

5. The combination with a transformer comprising a main and an auxiliary secondary winding, of a vapor converter comprising a pivotally mounted exhausted container provided with two main anodes, an auxiliary anode and a cathode, a relay, and a magnet adapted to tilt said container, said main anodes being connected to the terminals of said main winding and said cathode being connected to substantially the mid-point of said main winding through the energizing winding of said relay which, when deenergized, provides a path for current to flow from said auxiliary secondary winding to the energizing winding of said tilting magnet through said auxiliary anode and said cathode, and which, when energized provides a path for current to flow from said auxiliary secondary winding to the energizing winding of said tilting magnet without passing through said auxiliary anode and said cathode.

6. The combination with a vapor converter comprising a pivotally mounted exhausted container provided with main anodes, a liquid cathode and an auxiliary anode in contact with said cathode in the idle position, of a tilting magnet for said container, said magnet being provided with an operating winding connected in series with said cathode, said auxiliary anode and a source of alternating current when in its starting position and connected directly to said source of current when in its operative position.

7. The combination with a transformer comprising a main and an auxiliary secondary winding, of a vapor converter comprising two main anodes connected to the terminals of said main winding, a cathode connected to substantially the mid-point of said main winding through a direct-current load, and an auxiliary anode connected to said cathode through said auxiliary winding, whereby, in the event that the arc starts with the auxiliary winding as a cathode, the electromotive forces of said auxiliary-winding and of the respective sections of said main-winding alternately oppose and assist each other during successive half-cycles, the number of turns of said auxiliary-winding being such that the arc is killed during the half-wave in which said electromotive forces oppose each other.

In testimony whereof, I have hereunto subscribed my name this 18th day of March, 1918.

ALFRED L. AETHERTON.
